MANIFOLDING MACHINE

Charles F. Schmelz, Bridgeport, Conn., assignor
to Autographic Register Company, Hoboken,
N. J., a corporation of New Jersey

Application January 31, 1935, Serial No. 5,027

12 Claims. (Cl. 282—12)

This invention relates to autographic registers, and more particularly, to the type of register in which a record copy is retained in a suitable compartment provided for the purpose.

5 In the form of the invention herein disclosed, the invention is shown as applied to a portable type register in which the record copies or slips are stored in a record compartment located partially under the supply compartment for the 10 writing strips, and into which the slips are placed one after another as they are issued from the machine and torn off.

In such registers, the supply compartment as well as the record compartment are usually made 15 sufficiently long to accommodate the longest form or ticket which is used with the machine, but it is in many cases used with shorter forms than the maximum, thus, in most instances, leaving a considerable space in the supply and record 20 compartments.

When the machine is a portable machine, that is to say, one which may be carried around and handled promiscuously and must be taken up in the hand to write the bill or ticket, the supply pad is free to shift longitudinally, with the result that the strips become disarranged and 25 improperly folded and creased.

An object of this invention is to provide means in the supply compartment for holding supply 30 pads which are shorter than the supply compartment against shifting longitudinally in the supply compartment.

In the portable register disclosed in this application, the record slips are inserted by hand one 35 after another in the record compartment and caused to be collated on pins fixed in the compartment, or on a binder removably mounted in the compartment; and, to facilitate the proper collation of the record slips on these pins, the record compartment has, heretofore, been provided with an end stop limiting the movement and determining the position of the record slips 40 longitudinally in the record compartment, but an isolated end stop in the record compartment 45 has, heretofore, been troublesome because of its inaccessibility and because it was difficult to set in just the right position.

A further object of this invention is to provide 50 means whereby the end stop in the record compartment will be automatically located in proper and desired position by the adjustment of the end stop in the supply compartment.

This object of the invention is accomplished by 55 connecting the two end stops together as a unit and offsetting them longitudinally of the register by an amount equal to the offset between the front end of the supply pad, and the front wall of the supply compartment and the front wall of 60 the record compartment.

Other features and advantages will hereinafter appear.

In the accompanying drawing, which shows several embodiments of this invention—

Figure 1 is a plan view of the register with parts broken away to show the record compartment, the supply compartment, and the record strips in the supply compartment. 5

Fig. 2 is a longitudinal sectional view taken on the line 2—2 of Fig. 1, and showing the present 10 invention.

Fig. 3 is a perspective view of the end stops of the present invention in the form thereof illustrated in Figs. 1 and 2.

Fig. 4 shows an edge view of another embodiment of the present invention and its relationship 15 to the supply pad and record strips.

Fig. 5 is a similar view, but showing another form of this invention.

Fig. 6 is a similar view, but showing still another form of this invention. 20

As shown in the accompanying drawing, the register comprises a casing 10 having a platen 11 and a marginal frame 12. Under the platen there is a supply compartment 13 in which there 25 is supported a supply pad 14 of zigzag folded superposed continuous record strips. Record form strips 15 are led from the pad 14 over the rear end 16 of the platen and then forwardly under the margin frame 12 and over the platen 30 11 where they are interleaved with suitable transfer material not shown. Beyond the platen, the strips 15 are normally engaged by pins 17 which hold the strips in writing position on the platen. When it is desired to feed out a set of written 35 forms, the pins 17 are moved forwardly by means of a handle 18 and by mechanism forming no part of this invention, so as to project the leading ends 19 of the strips beyond a tear-off knife 20 and permit the strips to be grasped by hand 40 and pulled out of the machine until the next set of apertures 21 on the strips is again engaged by the pins 17 to intercept paper withdrawal and to limit the quantity of paper pulled out at one 45 form length.

The register frame 10 has a partition or false bottom 22 which forms the bottom of an upper compartment and on which the record supply 50 14 is supported, and between the false bottom 22 and the bottom 23 there is formed a lower record-receiving and storing compartment 24.

When the strips have been stopped by the pins 17 as above explained, they are torn off along the knife edge 20 and one of the resulting 55 tickets is usually inserted in the record storing compartment 24 when a door 25 at the projecting forward end of the record compartment is opened. The record slips 15—*a*, a quantity of which is shown in Fig. 2, are placed on pins 26 in the record compartment so as to hold them 60

properly collated, and to facilitate this, as pointed out above, the record compartment has heretofore been provided with an end stop in the form of a plate or partition between the false bottom 22 and the bottom 23, so that when the foot-edge of the record slip engaged this plate or partition, the apertures 21 in the slip would be located over the pins 26.

The adjustment of this plate or partition, because of the fact that it was located deep in the narrow record compartment 24, was extremely difficult to effect.

Further, as pointed out above, the supply compartment 13 is made sufficiently long to accommodate the supply pad 14 for the longest form with which the machine may be used. Since the maximum length form is seldom used, the record pad in such machines, as heretofore provided, was free to shift longitudinally in the supply compartment and, being light and usually carried around by hand or in the pocket from place to place, was shifted back and forth in the supply compartment, with the result that the pad became disarranged and the portion of the strips 15 from the pad to the platen became undesirably folded and creased.

To avoid this, the present invention provides in the supply compartment 13 an adjustable wall or end-stop device having its end stop 27 rising from the false bottom 22 and extending as close to the platen as is desired. At its upper edge, it is provided with a roll 28 so that the strips 15 may conveniently pass over it and between it and the platen without the risk of damage.

In the broader aspects of this invention, this end stop 27 may be adjusted in any suitable manner to more or less loosely engage the rear end of the supply pad 14 when the front end thereof is engaged by a wall 29 covering the pin mechanism and constituting the forward wall of the supply compartment.

However, according to the present invention in its preferred form, the end stop 27 is joined to a downwardly-extending end stop 30 in the record-slip compartment, 24, and these end stops are spaced from each other by a distance equal to the distance between the front wall 29 of the supply compartment and the front wall 31 of the record-slip compartment, so that, when the end stop 27 is adjusted to fit the particular length of supply pad 14 inserted in the machine, the end stop 30 for the record compartment will also be properly positioned in the latter.

This is accomplished, according to the present invention, by connecting the end stop 27 for the supply compartment with the end stop 30 for the record compartment by a bar 32, and preferably the end stop 27, bar 32, and end stop 30 are made as one integral piece, preferably Z-shaped as shown, and the false bottom 22 is provided with a slot 33 through which the bar 32 may extend from the supply compartment to the record compartment.

As shown in Figs. 1, 2 and 3, the bar 32 is for the most part located under the false bottom 22 and has a pair of wings 34 extending from each side and engaging the underside of the false bottom 22 at each side of the slot 33, so as to hold the end stop 27 against being raised from the false bottom 22. On the other hand, the end stop 27 itself extends beyond the slot 33 and rests on and is supported by the false bottom by its lower edge directly engaging the top of the same, so that, at that end of the bar 32, the two parts are held against separation in either direction, vertically.

From the wings 34, the bar 32 may extend upwardly and have the bent portion 35 thereof lying in the slot 33 so as to positively steady against the bar 32 from skewing in a horizontal plane. The end stop 30 is located directly under the portion 35 and at its bottom is provided with a backwardly bent ear 36 engaging the top of the bottom plate 23. The ear 36 is provided with a threaded hole 37 for receiving a clamp-screw 38 passing through a slot 39 in the bottom plate, so that, when the screw 38 is tightened, its head engages the margin of the slot 39 and holds the end stop assembly shown in Fig. 3 against shifting longitudinally of the register.

To facilitate the insertion of the end stop unit 15 in operative position in the register, the false bottom 22 is provided with slots 40 shown in dotted lines in Fig. 1, through which the end stop 30 and the wings 34 of the bar 32 may pass downwardly through the false bottom 22 and into the record 20 compartment.

After the assembly is inserted in place through the slots 40, it is moved longitudinally in the slot 33 (more or less depending upon the length of the pad 14 to be used with the register), the slots 40 being so located that even if the smallest supply pad be used with the register the end stop unit must be moved longitudinally after being inserted.

In adjusting the end-stop unit, it is merely necessary to loosen the screw 38 and push the end stop unit to the left as viewed in Fig. 2, then when the supply pad 14 is placed on the false bottom 33, the end stop unit is slid forwardly until it engages, or about engages, the rear edge of the pad, at which time the screw 38 is tightened. By doing this, the end stop 30 in the record compartment is automatically adjusted to proper position, for the longitudinal distance between the end stops 27 and 30 is substantially equal to that between the front wall 29 of the supply compartment and the front wall 31 of the record compartment.

The end stop unit may be made in different ways, several of which are illustrated herein. For instance, as shown in Fig. 4, instead of having the plate 23 slotted and engaged by the clamping screw 38, the bottom plate 23 may be made solid as shown in Fig. 4, and a clamp-screw 41 may be threaded in the bar 32. With this arrangement, after placing a washer 42, or other element which will bridge the slot 33 in the false bottom, on the screw, the screw is tightened in a threaded hole in the bar 32 to clamp the end-stop unit to the false bottom 22.

The bottom of the end 30, instead of being bent rearwardly as shown in Fig. 3, has a portion 43 bent forwardly so as to lie under a binder 44 on which the record strips 15a are stacked and prevent the record strips from passing between the lower edge of the end stop 30 and the bottom plate 23.

As shown in Fig. 5, the bar 32 may lie upon the false bottom 33 and only have the portion 35 thereof extend through the slot 33. In this case, the return bend or backwardly bent ear on the end stop 30 preferably has an extension 45 provided with an ear 46 extending downwardly in the slot 39 to hold the end-stop unit from skewing.

Again, as shown in Fig. 6, the end-stop unit 70 may be further modified so as to have the bar 32 lying on top of the bottom plate 23, in which case the end stop 30 extends upwardly from the bar 32.

Other variations and modifications may be made within the scope of this invention and por- 75

tions of the improvements may be used without others.

Having thus described the invention, what is claimed as new and for which it is desired to obtain Letters Patent, is:—

- 5 1. A portable manifolding register having a supply compartment for a zigzag folded pack of continuous record strips folded at ticket length intervals, and a record compartment for storing 10 record tickets issued from said supply compartment and severed from said record strips, each of said compartments being longer than the length of a form; an end stop in the supply compartment for holding the supply pack against 15 longitudinal movement in the supply compartment; an end stop in the record compartment for determining the position of the tickets in the record compartment; and means interconnecting 20 said two end stops for coordinate adjustable movement so that when one end stop is moved to position to accommodate a form of a particular length the other end stop will be moved to position to accommodate a form of that particular length.
- 25 2. A manifolding machine having a frame divided horizontally to form a supply compartment for continuous record strips and below it a storage compartment for record slips severed from one of said strips, one end of said storage 30 compartment projecting beyond the upper portion of the frame and having an entrance opening at the top of its projecting portion for receiving record slips inserted downwardly and inwardly therein, the supply compartment and the 35 storage compartment each having a front wall and said front walls being offset longitudinally; an end stop unit having an end stop in each of said compartments; and means connecting said end stops, said end stops being offset longitudinally by the amount of the offset between the 40 front wall of the supply compartment and the front wall of the storage compartment.
3. A manifolding register comprising a frame having a horizontal false bottom dividing said 45 frame into an upper and a lower compartment, and an end-stop device guided for longitudinal movement on said false bottom and having one end stop extending upwardly into said upper compartment, and having also another end stop 50 extending downwardly, into said lower compartment, and means for clamping said device in a predetermined position longitudinally relatively to said frame.
4. A manifolding register comprising a frame 55 having a longitudinally-slotted false bottom dividing said frame into an upper and a lower compartment, a longitudinally slotted bottom plate for the lower compartment, an end-stop device shiftable longitudinally and guided by the slot in the 60 false bottom, and having end-stops extending vertically in opposite directions into the upper and lower compartments, respectively, and means carried by said downward extension and passing through the slot in the bottom plate for clamping 65 said end-stop device against accidental displacement thereon.
5. A manifolding register comprising a casing 70 having a longitudinally-slotted false bottom, an end-stop device consisting of a bar guided for longitudinal shifting in said slot and a pair of end-stops extending upwardly and downwardly 75 therefrom, respectively, and means for clamping said device against shifting longitudinally in said casing.
6. A manifolding register comprising a casing having a longitudinally-slotted false bottom, an end-stop device consisting of a bar guided for longitudinal shifting in said slot and a pair of end-stops extending upwardly and downwardly 5 therefrom, respectively, the end-stop at one end of the bar resting on said false bottom, and said bar having side wings engaging the underside of said false bottom, for holding that end of the device against separation from said false bottom, 10 and means for clamping said device against shifting longitudinally in said casing.
7. A manifolding register comprising a casing having a longitudinally-slotted false bottom, an end-stop device consisting of a bar guided for 15 longitudinal shifting in said slot and a pair of end-stops extending upwardly and downwardly therefrom, respectively, the end-stop at one end of the bar resting on said false bottom, and said bar having side wings engaging the underside 20 of said false bottom, for holding that end of the device against separation from said false bottom, and a clamp screw carried by said bar and extending through said slot, for holding said device against shifting.
- 25 8. A manifolding register comprising a casing having a slotted false bottom and a longitudinally-slotted bottom plate, and an end-stop device having a bar resting on said false bottom, the ends of said bar having, respectively, upwardly 30 and downwardly-extending end-stops, the latter passing through said slot and having a return-bend portion resting on said bottom plate and provided with an ear guided in the slot of said bottom plate, and a clamp screw for holding said 35 return-bend and bottom plate together.
9. A manifolding register comprising a casing having a longitudinally-slotted false bottom, and a slotted bottom plate, and an end-stop device consisting of a bar resting upon said bottom plate, 40 and having at its ends vertical end-stops, the forward end stop terminating at the underside of said false bottom and projecting above the same, and a clamp screw passing through the slot in the bottom plate and engaging said bar for holding 45 the device in position.
10. A manifolding machine having a frame divided to form a supply compartment for continuous unwritten record strips and adjacent it a storage compartment for written portions of said 50 slips; an end-stop unit having an end-stop in each of said compartments, and means connecting said end-stops together; and means for securing said end-stop unit against casual movement.
11. A manifolding machine having a frame 55 divided horizontally to form a supply compartment for continuous record strips and below it a storage compartment for record slips severed from one of said strips; an end-stop in said supply compartment; and means extending into said 60 storage compartment for controlling the position of said end-stop.
12. A manifolding machine having a frame divided horizontally to form a supply compartment for continuous record strips and below it a storage compartment for record slips severed from one of said strips; an end-stop in the storage compartment; and means extending into the supply compartment for controlling the position 65 of said end-stop.

CHARLES F. SCHMELZ.
